(57) **CLAIM**

The ornamental design for a sock, as shown and described.

DESCRIPTION

FIG. 1 is a front, left perspective view of a sock showing our new design;

FIG. 2 is a front, right perspective view thereof;

FIG. 3 is a left side view thereof;

FIG. 4 is a right side view thereof; and,

FIG. 5 is a rear view thereof.

The uneven-length broken lines immediately adjacent to the photographic area define the bounds of the claimed design. The even-length broken lines showing the remainder of the sock represent unclaimed environmental subject matter. None of the broken lines form part of the claimed design.
